US00D903106S

(12) **United States Design Patent** (10) Patent No.: **US D903,106 S**
(45) Date of Patent: **** Nov. 24, 2020**

(54) **INJECTION DEVICE**

- (71) Applicant: **Sanofi-Aventis Deutschland GMBH**,
Frankfurt am Main (DE)
- (72) Inventors: **Paul Richard Draper**, Warwick (GB);
Stuart James King, Warwick (GB);
James Leslie Rhodri Jones, Warwick
(GB)
- (73) Assignee: **Sanofi-Aventis Deutschland GMBH**,
Frankfurt am Main (DE)
- (**) Term: **15 Years**
- (21) Appl. No.: **29/709,206**
- (22) Filed: **Oct. 11, 2019**

Related U.S. Application Data

- (62) Division of application No. 29/646,487, filed on May
4, 2018, now Pat. No. Des. 878,562.

CLAIM

The ornamental design for an injection device, substantially as shown and described.

DESCRIPTION

The patent or application file contains at least one drawing executed in color. Copies of this patent or patent publication with color drawing(s) will be provided by the Office upon request and payment of the necessary fee.

FIG. 1 is a perspective view of an injection device;

FIG. 2 is a front view thereof;

FIG. 3 is a back view thereof;

FIG. 4 is a side view thereof;

FIG. 5 is an additional side view thereof;

FIG. 6 is a top view thereof; and,

FIG. 7 is a bottom view thereof.

1 Claim, 5 Drawing Sheets
